STRAND GUIDING APPARATUS

De Witt D. Merrick, Cranford, N. J., assignor to
 Western Electric Company, Incorporated, New
 York, N. Y., a corporation of New York

Application September 29, 1938, Serial No. 232,277

9 Claims. (Cl. 57—138)

This invention relates to a strand guiding apparatus and more particularly to a cable unit guide for cable forming apparatus.

In forming cables, for example telephone cables, of a plurality of cable units, consisting of groups of electrical conductors with insulating covers of different color combinations, it is frequently desirable to guide the cable units in selected paths just prior to their being inter-twisted by a cable forming apparatus so that the cable units may be readily distinguished one from the other at either end of the completed cable. It has been found advantageous to guide the cable units in definite and substantially equally spaced paths just prior to the twisting thereof to cause a uniform lay of the units in the cable. However, cables varying in the number of selected cable units require variation in the positions of the guides for the cable units.

An object of the invention is to provide a simple and efficient apparatus for selectively guiding varying numbers of strands.

With this and other objects in view, the invention comprises a support apertured to receive a selective number of guide elements removably and adjustably positioned in the aperture and aided in the adjustment thereof by adjacent graduations on the support to evenly guide strands therethrough.

Other objects and advantages will be apparent from the following detailed description taken in conjunction with the accompanying drawing, wherein

Fig. 1 is a front elevational view of the apparatus illustrating one arrangement of the guide elements;

Fig. 2 is a vertical sectional view taken along the line 2—2 of Fig. 1, and

Fig. 3 is a side elevational view of the apparatus, a support therefor being shown in section.

The embodiment of the invention shown in the drawing is adapted to guide cable units 10 from individual supply spools (not shown) and direct them in spaced paths to a cable forming apparatus of the type shown in the copending application of Lester O. Reichelt, Serial No. 597,947, filed March 10, 1932.

This embodiment of the invention comprises a support 11, circular in general contour and having arcuate apertures 12, 13, 14 and 15 therein. A central aperture 16 is also formed in the support. The apertures 12 to 15 inclusive are arcuate in general contour, the apertures 12 and 13 being disposed adjacent the outer periphery of the support and forming an interrupted circular

guide receiving aperture, the apertures 14 and 15 in a like manner forming an interrupted circular guide receiving aperture concentric with and lying between the outer apertures 12 and 13. A suitable bracket 18 apertured at 19 has an annular recess for receiving the support 11, to mount the support in general alignment with the axis of the completed cable. The support is removably secured in place by studs 20 carried by the bracket 18, extending through apertures (not shown) in the support and provided with wing nuts 21 on the outer ends thereof.

A plurality of guide elements 25 are provided, which elements are tubular in general contour, having at the entrance ends thereof outwardly flared integral flanges 26 and at the exit ends threads for receiving nuts 27. Washers 28 are positioned between the nuts 27 and the adjacent wall of the support 11, as shown in Fig. 2. Diametrically opposed side walls 29 of the tubular guide elements 25 are flattened, as shown in Fig. 1, to prevent possible rotation of the guide elements when they are locked in place on the support. The flange 26 of each of the guides extends over the adjacent walls of the support and in a like manner the washer and nut engage the adjacent walls of the supports, but upon the opposite side from the flange, for the securing of the guide elements in place.

Figs. 1 and 2 illustrate an annular raised portion 32 adjacent the outer periphery of the support 11 having graduations 33 equally spaced in radial formation therearound, dividing the surface of this projection into sections representing degrees of a circle about the center line of the support.

In the present illustration, eight cable units are being guided from supplies (not shown) to a cable forming apparatus which intertwists the cable units together. In the present illustration, six of the cable units are directed through outer guide elements and two of the cable units are directed through inner guide elements. The twist applied to the group of cable units is carried back to the exit end of the guide elements 25 and a short distance from the support 11 is positioned a sizing polisher 35 mounted upon a suitable support and apertured to receive a group of inter-twisted cable units. Therefore, in view of the fact that in this embodiment the cable units are directed toward each other in a twisting motion to pass through the polisher 35, a truncated cone-shaped guide member 38 is mounted upon the support at the intermediate annular position thereof to separate the outer cable units from the

inner cable units and further assist in guiding them to the polisher. The guide member 38 is hollow and has disposed in its outer or exit end an apertured portion 39 through which the inner cable units pass during their advancement.

If the cable being formed is to have eight cable units, it is important that these units be directed in predetermined spaced paths so that they will lie uniformly in the finished cable. The guide elements 25, through the aid of the graduations 33, are disposed, six in the outer apertures equally spaced from each other and two in the inner apertures equally spaced from each other and each lying in radial planes equidistant from pairs of the outer guide elements. If desired, graduations may also be disposed upon the intermediate portion of the support 11 adjacent the inner apertures 14 and 15.

If a cable of another type required, for example, twelve cable units, the apparatus may be conditioned to guide the twelve cable units at substantially equally spaced positions. This may be accomplished by loosening the nuts 27 upon the guide elements now positioned in the support and moving them so that an additional guide element may be disposed in each of the apertures 12 to 15 inclusive, and all of the guide elements equally spaced and locked in place. When an odd number of cable units is employed, the aperture 16 may be used to guide the cable unit through and for this reason a guide element may be disposed therein.

It is apparent that the apparatus may be readily conditioned to guide in equally spaced positions any desired number of cable units, and to accurately position the cable units so that they will lie uniformly when twisted together.

The embodiment of the invention herein disclosed is illustrative only and may be widely modified and departed from in many ways without departing from the spirit and scope of the invention as pointed out in and limited only by the appended claims.

What is claimed is:

1. A strand guiding apparatus comprising a support having an elongate aperture therein, a guide element removably disposed in the aperture, and means to secure the element in any selected position in the aperture.

2. A strand guiding apparatus comprising a support having an elongate aperture therein, a guide element disposed in the aperture, means to secure the element in any selected position in the aperture, and graduations adjacent the aperture for the definite positioning of the element.

3. A strand guiding apparatus comprising a support having arcuate apertures disposed therein, and guide elements disposed in the apertures and adjustably secured in selective positions relative to each other.

4. A strand guiding apparatus comprising a support having arcuate apertures concentrically disposed therein, and guide elements disposed in the apertures and adjustably secured in selective positions relative to each other.

5. A strand guiding apparatus comprising a support having an arcuate aperture therein, a guide element receivable in any selected position in the aperture, and means to secure the element to the support.

6. A strand guiding apparatus comprising a support having arcuate apertures concentrically disposed therein, elements adjustably disposed in the apertures to guide strands in selectively spaced positions, and a guide member disposed adjacent the support between the apertures to space the strands passing from the elements from each other.

7. A strand guiding apparatus comprising a support having an elongate aperture therein, a tubular guide disposed in the aperture, and means to secure the guide to the support in any selected position in the aperture.

8. A strand guiding apparatus comprising a support having an elongate aperture therein, a tubular guide disposed in the aperture and having a flat portion adjacent a wall of the aperture to eliminate rotation of the guide, and means to secure the guide to the support in any selected position in the aperture.

9. A strand guiding apparatus comprising a plurality of guides for strands, and a support having a plurality of elongate apertures spaced to removably receive numbers of the guides variable with the number of strands to be guided and at variable relative positions.

DE WITT D. MERRICK.
